ARRANGEMENT FOR COVERING
SHIP HULLS

Ernst Loewenstein, San Francisco, Calif.

Application February 28, 1944, Serial No. 524,187

2 Claims. (Cl. 114—84)

1. This invention relates to a cover for protecting ships.

An object of the invention is to provide protection for the bottom and side platings of ships up to the waterline by layers of protective material, the material of such covers being of such nature as to offer smooth surfaces so as to materially diminish the friction between the ship and the water.

Particularly, an object of the invention is to provide an arrangement for protecting the bottom and side platings of ships below the waterline by applying to said portions of the ship strips of waterproof smooth material so as to have said sheets or strips completely conform to the curvature of the sides and bottom of the ship, and to hold the sheets in such position, yet permitting the easy replacement of such covering sheets.

Another object of the invention is to provide a protective covering for the sides and bottom of a ship in the form of sheets which are securely held in place, fully conforming to the curvature and shape of the ship, and presenting a smooth anti-friction surface in the water.

Other objects of the invention together with the foregoing will be set forth in the following description of the preferred method, and the preferred embodiment of means for practicing the same, which is illustrated in the drawings accompanying and forming part of the specification. It is to be understood that I do not limit myself to the embodiment disclosed in said description and the drawings as I may adopt variations of my preferred forms within the scope of my invention.

Preferred embodiments of my invention are clearly illustrated in the accompanying drawings wherein:

Fig. 1 is a side view of a ship showing somewhat diagrammatically the arrangement of the protective sheets on the sides and bottom of a ship.

Fig. 2 is a fragmental sectional view of a form of securing means for the top edges of the sheets, the section being taken on lines 2—2 of Fig. 1.

Fig. 3 is a fragmental sectional view showing an illustrative embodiment of the securing of adjacent vertical edges of the sheets, the section being taken in lines 3—3 of Fig. 1.

Fig. 4 is a fragmental sectional view showing the holding of adjacent horizontal edges of the protective sheets on the ship, the section being taken on lines 4—4 of Fig. 1.

Fig. 5 is a fragmental side view showing the arrangement of the vertical and horizontal holding flanges at the meeting edges of adjacent sheets.

2. Fig. 6 is a fragmental sectional view showing another form of attachment of the top edges of sheets to the ship, which form is preferably used in connection with newly built ships.

5. Fig. 7 is another modified form of holding the top edges of the protective sheets.

Fig. 8 is a fragmental view of the clamping means for adjacent edges of the protective sheets on newly constructed ships, designed for the use of such protective sheets.

Fig. 9 is a fragmental sectional view of another form of clamping for the meeting edges of adjacent sheets.

Fig. 10 is still another form of clamping the meeting edges of adjacent sheets to the ship, and

Fig. 11 is a perspective somewhat diagrammatic view of the step of the method for applying the sheets to the sides of the ship.

In my method of applying protective coverings to ships below the waterline, the plates of the ship are first cleaned in the usual manner. In the event the protective sheets are applied to old ships, naturally the bottom and sides of the ships must be cleaned of weeds, barnacles and other accumulations. In the event that the covering is applied to new ships, the usual cleaning of the plates as now done suffices.

The sheets, or films used for covering the underwater portion of a ship may be of various types of waterproof material of the type which is not affected by sea water and which provide an absolutely smooth surface. It is preferable that such material be flexible, such as sheets or films of plastic. It is also preferable, in connection with certain steps of my method that the materials, such as plastic, be pliant in the presence of heat and harden after cooling. Methyl methacrylate, for instance is a suitable material for such covering.

The sheets of material are placed upon the ship in the following manner. Horizontal strips or sheets of material are placed from one side of the bow and around the bow to the other side in parallel adjacent horizontal strips. The stern of the ship is similarly protected. These sheets of material are bent or shaped to conform to the shape of the bow or stern respectively over the same streamlined or sharp bow or stern as that of the ship. Over these bow and stern pieces are placed the horizontal side sheets made of suitable width and length for convenient handling. At the bottom or keel of the ship, the strips are again placed around from one side of the keel under and over to the other side of the keel so as to completely cover the extreme bottom of the

ship. The bottom and side sheets extend contiguously along the whole length of the ship on each side from bow to stern.

The sheets are secured in place by various suitable steps, suitable adhesive may be used on the inner surfaces of the sheets so that they adhere to the metal plates of the ships or to the underlying sheets of protective covering. The method as shown in Fig. 11, shows one mode of application of heat for shaping the sheets to the outline of the ship.

The sheet 1 is unrolled on the side of the ship 2 a pressure roller 3 is rolled over the sheet 1. This roller 3 has a heating element therein, not shown. The heating element may be electrical, 15 or any other suitable type. The roller 3 is made of a heat conducting material. In this form the pressure roller is carried on a frame 4 and pressure is exerted on the roller by roller plungers 6 which are urged by springs 7 against the roller 3, but which are adjustable in the frame 4 so as to conform to the curvature which the roller 3 must assume in conformance with the contour of the ship plates over which the respective protecting sheet 1 is to be placed. As the roller 3 is rolled over the sheets at a moderate speed it heats the plastic sheet 1 and thus the sheet will be pliable to the contour of the ship. Also, if there is any adhesive used on said covering sheet 1, the same under the heat will become more adhesive and will hold the plate in place.

In the event the mechanical attachment or securing of the sheets 1 is desirable, the respective edges of the protective sheets 1 can be secured by suitable stretching clamping mechanisms which are preferably releasable so as to facilitate removal and replacement of the respective protective sheets. When the mechanical stretching and clamping means are used for holding the edges of the sheets and the sheets in place, the steps of the method include the stretching of the sheets by means of these clamping mechanisms so as to stretch them over into close contact with the plates which they cover. In addition, the heating and pressure roller 3 may be and is usually applied to have a closer conformance to the contour of the ship.

The bow sheets 8, as previously explained, extend from one side to the other side of the ship across and over the bow. These bow sheets 8 are covered by the side sheets 1 which overlie the bow sheets 8 adjacent the bow of the ship. Similar arrangement is provided at the stern of the ship.

In connection with the ships already built, the securing and stretching mechanisms are attached to the ship by welding or other suitable manner. In the herein form for the top horizontal edges of the sheets 1, a flange 9 is welded all along the full length of the ship on both sides at about the water line. This flange 9 extends away from the plate 11 of the ship and has a downward rim 12 spaced from the plate 11. This rim 12 is inclined outwardly and away from the plate 11 so that the space between the plate 11 and the flange rim 12 converges upwardly. A wedge block 13 is inserted in the space between the plate 11 and the flange 12 and is jammed tightly in place in any suitable manner, such as by a bolt or screw 14, which latter has its head on the outside of the top of the flange 9 for convenient access. The top edge of the sheet 1 is played around the top side of the wedge block 13 so that as the wedge block 13 is drawn tightly into the tapering space between the plate 11 and the flange rim 12, the edge of the sheet 1 is tightly jammed in place.

If it is necessary, a waterproofing seal may be provided as a coating on this portion of the sheet 1 so as to positively prevent the seepage of water into and through this clamping device. In this manner the upward stretching of the covering sheets 1 is accomplished. At the lower edge of the sheet 1 and at the top edge of the keel sheets 16, or between adjacent horizontal edges of the adjacent strips or sheets, a double clamping mechanism is utilized. An illustrative embodiment is shown in Fig. 4 where the side sheet 1 is extended over the base 17 of a flange 18 and is secured thereover by a clamping strip 19, which latter is held in place by suitable screws or bolts 21. The downwardly extended rim flange 22 of the retainer flange 18 diverges downwardly from the plate 11 so as to provide a tapering space 23 between the plate and the lower rim flange 22. A wedge block 24 is tightly wedged into the space between the rim flange 22 and the plate 11 by means of a screw or bolt 21. The top edge of the keel sheet 16 is played around the wedge block 24 so as to be tightly jammed in place and stretch the keel sheet upwardly and tightly around the keel of the ship.

The vertical edges of the adjacent sheets 1 or keel sheets 16 are stretched and clamped together by double clamp elements in the form of double retaining flanges 26 as shown in Fig. 3. These double retaining flanges 26 extend vertically between the vertical edges of the adjacent strips of material. Each of these double retaining flanges 26 have side rim flanges 27 which extend in spaced relation to the plate 11 vertically intersecting the horizontal flange arrangements heretofore described substantially in the manner shown in Fig. 5. The respective rim flanges 27 are also inclined with respect to the plate 11 so as to provide oppositely tapering vertical spaces 28. In each tapering space 28 is wedged a wedging block 29, around which latter is placed the vertical edge of the respective sheet 1 or keel sheet 16. Each wedge block 29 is tightened in place by a suitable screw or bolt 31. By the clamping of the vertical edges of the protecting sheets in this manner the sheets 1 or the keel sheets 16 are stretched horizontally. By thus clamping and stretching the respective protecting sheets and the added application of the heated roller, the sheets will truly conform to the streamline or contour of the ship as designed. The same construction is repeated throughout and around the ship as frequently or as spaced as needed in accordance with the length and width of the strips and materials used.

The clamping of the protecting sheets to prefabricated parts of ships in the course of building can be accomplished in such a manner as to conceal the clamping mechanism within the streamline of the ship and thereby avoiding any protruding parts. Various illustrations of such concealed clamping means are shown in the forms illustrated in Figs. 6 to 10 inclusive. In these figures, in the course of prefabrication, the plates 32 of the ship parts are provided with an indent 33. These indents 33 are arranged horizontally and vertically at the places where the edges of the sheets will lie. Into these indents are clamped wedging blocks 34 which are tightened and held in place by suitable screws or bolts 36. The edge of the sheet 1 can be placed around the indent's bottom as shown in Fig. 6 and then tightly clamped by the wedge block 34.

Another streamlined application is shown in Fig. 7 where the sheet 1 is extended over the out-

side of the wedge block 34 and then around the top of the wedge block 34 downwardly over the indent 33 into a substantially complete loop and then clamped in place. In this form the outside surface of the wedge block 34 is also protected. It is to be noted that in all these forms the wedge block 34 is in the form of a strip extending the full length of the indents 33, or it may be made of shorter sections clamped in place contiguously in the indents 33. The same structure can be used for securing two adjacent edges of adjacent sheets as shown in Fig. 8. In this form the edges are extended inside the indent 33 and over the bottom of said indent and then the wedge block 34 is clamped over both edges which extend from both directions of the sheets 1 and thus hold the edges of two adjacent sheets in place.

In Fig. 9, the same arrangement is shown substantially as in Fig. 8 except that two clamping blocks or strips 37 are used, one for the lower and one for the upper edges of the covering sheets 1. The two clamping blocks or strips 37 are tightened and secured in place by separate sets of suitable bolts or screws 38. In Fig. 10 the arrangement shown in Fig. 9 is shown in application where each of the sheets 1 has its respective edge played entirely around the respective wedging or clamping block 37 into opposite loops and then the whole unit is tightened in place by the aforesaid screws or bolts 38.

While various forms of attachment of the invention are herein illustrated and others may be used, in general the object is accomplished by stretching and shaping the sheets over the plates of the ship either in prefabricated parts or units or in completed or even in older ships to securely and completely cover and protect the plates. The sheets can be removed and replaced by loosening the respective clamps or by stripping them off and replacing them with other sheets which, in the presence of heat will be pliant and conform and adhere to the plates of a ship. The applying and replacing of such protective sheets is a simple operation. It entirely eliminates the scraping of the bottoms of the ships, it eliminates the usual evils of painting, it provides a smoother surface than painting. The smooth surface that can be obtained by sheets herein described improves the efficiency of the ship because of diminished friction.

I claim:

1. A protective covering for the outside surface of the underwater portion of a ship, comprising a plurality of water resistant sheets of smooth outer surface laid on said surface to cover the same, and securing elements on the side of the ship and along the edges of the respective sheets to tightly hold said sheets and seal said edges thereof, said securing means including a system of flanges on the sides of said ship forming a system of channels of tapering cross section, and clamp elements holding the respective edges of said sheets wrapped around the sides of the clamp element in contact with said channel and being wedged into the respective channels.
2. A protective covering for the outside surface of the underwater portion of a ship, comprising a plurality of water resistant sheets of smooth outer surface laid on said surface to cover the same, and securing elements on the side of the ship and along the edges of the respective sheets to tightly hold said sheets and seal said edges thereof, said securing means including a system of flanges on the sides of said ship forming a system of channels of tapering cross section, and clamp elements holding the respective edges of said sheets against and wedged into the respective channels, and means to detachably fasten said clamp elements into said channels.

30 ERNST LOEWENSTEIN.
